R. C. DOWNING & L. C. NICHOLSON
CURRENT TRANSFORMER.
APPLICATION FILED APR. 14, 1915.

1,278,121.

Patented Sept. 10, 1918.

UNITED STATES PATENT OFFICE.

RICHARD C. DOWNING, OF SYRACUSE, AND LLOYD C. NICHOLSON, OF BUFFALO, NEW YORK, ASSIGNEES TO NIAGARA ELECTRIC IMPROVEMENT CORPORATION, A CORPORATION OF NEW YORK.

CURRENT-TRANSFORMER.

1,278,121.

Specification of Letters Patent Patented Sept. 10, 1918.
Application filed April 14, 1915. Serial No. 21,247.

To all whom it may concern:

Be it known that we, RICHARD C. DOWNING and LLOYD C. NICHOLSON, citizens of the United States, residing, respectively, at Syracuse, in the county of Onondaga, State of New York, and Buffalo, in the county of Erie and State of New York, have invented certain new and useful Improvements in Current Transformers, of which the following is a specification.

Our invention relates to current transformers and particularly to current transformers for use on so-called high tension electric circuits.

Heretofore it has been customary to construct such transformers with a very short closed iron magnetic circuit which would necessarily bring the high potential primary winding in close proximity to the turns of the low potential secondary winding in order that the magnetizing component of the primary current should be relatively small and preferably negligible. In order to insulate the primary and secondary coils of such a transformer from one another some form of solid insulation was used and generally was supplemented by immersing the suitably supported coils in a tank of oil and providing specially constructed leads thereinto to the high potential winding. Such transformers have been used to measure quite accurately the current in the high tension circuit, and, in conjunction with a potential transformer, and watt meter, the power delivered by the high potential circuit. Such transformers are however expensive and complicated. According to our invention we construct a transformer having a substantially closed iron magnetic circuit, in which air space is depended upon substantially wholly for insulation between the high tension primary and the low tension secondary windings the windings being supported out of contact with one another and separated from one another by an amount sufficient to produce an air dielectric between the windings which will resist high potential break-down stresses. Such a transformer may be constructed much more cheaply and may be located out of doors and

the insulation is much more reliable than the forms of insulation heretofore depended upon in such transformers. Owing to the air space insulation used in our transformer and the consequently long iron core the magnetizing component of the primary current may be relatively large so that the secondary current is thrown somewhat out of phase with the high tension line current. When used for measuring the power delivered by the high tension line, we provide means for correcting this phase relation so as to bring the secondary current substantially into reverse phase with the line current so that the power delivered may be more accurately measured.

Further and more specific objects, features and advantages will more clearly appear from the detail description given below taken in connection with the accompanying sheet of drawings which forms a part of this specification and illustrates a transformer embodying our improvements in their preferred form.

Referring now to the drawings, Fig. 1 is a side elevation of a current transformer constructed according to our invention.

Fig. 2 is a vertical section taken on line 2—2, Fig. 1.

Fig. 3 is a plan view.

Fig. 4 is an enlarged transverse section taken through the primary coil.

Fig. 5 is an enlarged transverse section taken through the secondary coil.

Referring to the drawings in detail, like numerals of reference refer to like parts in the several figures.

As a means of mounting or supporting the transformer we have shown a pole A provided with a cross-piece a at its upper end to which the transformer is secured. The transformer has a channel-shaped base B which is secured to the cross-piece a in any approved manner, and rising from said base are two insulator pins C on which are mounted insulators c surmounted by cast iron caps D.

Arranged centrally between the insulators c is the secondary coil E of the transformer.

- This coil is wound transversely around an iron core F around which is wound friction tape f or other similar material. This secondary coil or winding is preferably of ordinary insulated wire, the two ends of which terminate, as at G, to which ends are adapted to be secured feed wires for any purpose or use. The iron core may be constructed in any approved manner, such as 5 by means of laminated rings, or otherwise, and after the secondary winding E is applied to the tape-covered core F, a protecting casing H of weather proof tape or the like is applied thereto.
- 10 The secondary coil and iron core rest upon the base B and are held against movement lengthwise thereon by two spaced retainer members I secured to said base and bearing against the opposite sides of said 15 coil. The secondary coil and core are further held rigid by means of braces J which are secured at one of their ends to the coil in any approved manner, said braces having their other ends secured to the insulator pins 20 C, as at j.

The insulator pins C, insulators c, and metallic caps D constitute two insulated supports for which any other form of insulator support may be substituted, and on each of 25 these supports are secured a pair of spaced retainer members K, preferably formed of wood. The last-mentioned retainer bars are secured to the supports by means of bolts k which enter or may be fastened into the 30 caps D.

L represents the primary coil which is passed through the secondary coil, both of 35 which are of ring formation arranged at right angles to each other, and each passes centrally through the other so that they are spaced from each other approximately the 40 distance of one-half of the inner diameter of each, these spaces serving as air insulating spaces and being the means of insulation 45 depended upon for insulation between the coils, the insulators c serving to insulate the high tension primary coil from the ground.

The primary coil is composed of a number 50 of turns or convolutions of insulated wire l, the number of turns or convolutions used and the size of same are dependent on the ratio of the transformer, and to this coil the line wire M is secured. This coil is also surrounded by a protective casing of any approved construction, which we preferably 55 form by surrounding the same with one layer of friction tape given two coats of shellac, which coated tape when dry is surrounded by a layer of asphalt tape coated 60 with asphaltum. The primary coil is held in position by the retainer members K, it being entered between the two opposite pairs of these members at opposite sides of the vertical center of the coil and clamped in

position by means of bolts N which are 65 passed through said retainer members and cause said members to be drawn toward each other to securely clamp the coil.

By arranging the coils in the manner described; that is, by passing one of the coils 70 axially through the other and arranging them at right angles all portions of one are exactly equal distances from some portion of the other coil and the air insulating space between the coils is the same throughout 75 the apparatus.

O designates a resistance coil and O¹ a condenser which may be mounted on the primary coil, as shown, and these have connection with the line wires M by means of wires 80 o, this resistance and condenser (either or both) being therefore shunted across the primary coil for the purpose of changing the time phase angle of the line current 85 relative to the current of the secondary coil and to give accuracy of ratio through a wide range of current values.

By connecting the resistance O across the primary, we believe a component of current is produced in the high tension line in advance of the load current component in the transformer primary which serves to bring the resultant line current (otherwise thrown out of reverse phase with the secondary current by the lagging exciting current component thereof) substantially into reverse phase with the secondary current so that when the transformer is used in conjunction with other apparatus for measuring power 90 the power factor conditions of the primary circuit will be represented with substantial accuracy. In such case however the relative values of the secondary current and the current in the high potential line is altered 95 so that they do not correspond with the relative number of turns of the two windings. However this may be calculated for in computing the power or load current delivered by the high potential line or the ratio may be corrected to correspond with the ratio desired 100 between secondary current and high tension load current, by changing the number of turns on either one of the coils. Or 105 this difference in ratio produced by current passing through the resistance D may be 110 corrected by putting in the condenser D¹ as described. The condenser produces we believe a component of the line current 90° in advance of the voltage across the primary 115 terminals, so that the ratio of transformation is affected thereby in an opposite manner from that in which it is affected by the current in resistance D, so that by suitably 120 designing the combination of resistance and condenser, the phase angle of the line current may be corrected without substantially 125 affecting the ratio of transformation. But as above pointed out this refinement is not

- essential as the ratio may be corrected by changing the number of secondary turns. The above theory of operation with respect to the resistance O and condenser O' we believe to be correct but, in any event, we find from experience that the arrangement described does materially correct the phase error of such a series transformer and enables its use for accurate power measurements.
- From the above it will be clear that we have provided an extremely economical and substantial construction for series or current transformers for operation on high tension lines. Should the air insulation of the transformer fail between the primary and secondary no harm is done except the puncture of a small amount of insulating material wrapped around the primary and secondary turns. Immediately the voltage is removed from the transformer the main insulation depended upon between the primary and secondary is restored automatically by change of atmosphere. Also there is no solid insulation directly between the two coils on which moisture might collect to materially decrease the insulation between the coils, so that the construction is particularly adaptable to be placed out of doors.
- By using means for correcting the phase angle, the error caused by the relatively large exciting current made necessary by the use of the air insulation, is substantially corrected. Should the supporting insulators be punctured or fail for any reason, the replacement of such an insulator is a very simple and inexpensive matter as compared with the replacement of the special insulating means heretofore used in this type of transformer. However, as the supporting insulators are not depended upon for insulation between the coils, the thickness and number of such insulators may be so chosen that it would be practically impossible to have puncture of the supporting insulators, as they would, so to speak, be protected by air insulation of less value between the coils. Of course when used merely for the measurement of current the phase corrective features are unnecessary. The transformer may be used for tripping overload relays and for other purposes in conjunction with various other apparatus as will be apparent to those skilled in the art.
- It is also to be understood that many other changes and modifications may be made and the invention in its broader aspects embodied in widely differing forms of apparatus.
- Having thus described our invention, what we claim is:
1. A transformer having a substantially closed iron magnetic circuit, a high tension primary winding and a low tension sec-
  - ondary winding operatively related thereto, supporting means for said windings arranged to support them out of contact with one another and separated from one another by an amount sufficient to produce an air dielectric between the windings that will resist high potential break-down stresses, and means for compensating for the change in phase angle between the primary current and secondary current due the energizing component of current in the primary winding.
  2. A transformer having a substantially closed iron magnetic circuit, a high tension, power current carrying primary winding and a low tension secondary winding operatively related thereto, supporting means for said windings arranged to support them out of contact with one another and separated from one another by an amount sufficient to produce an air dielectric between the windings that will resist high potential break-down stresses and whereby the atmosphere is depended upon as the main insulation between said primary and secondary windings and means for correcting the phase angle relationship between the primary current and secondary current.
  3. A transformer having a substantially closed iron magnetic circuit, a high tension, power current carrying, primary winding and a low tension secondary winding operatively related thereto, supporting means for said windings arranged to support them out of contact with one another and separated from one another by an amount sufficient to produce an air dielectric between the windings that will resist high potential break-down stresses, and means for correcting the phase angle relationship between the primary current and secondary current, said means comprising a resistance connected in parallel relation to current in the primary winding.
  4. A transformer having a substantially closed iron magnetic circuit, a high tension, power current carrying, primary winding and a low tension secondary winding operatively related thereto, supporting means for said windings arranged to support them out of contact with one another and separated from one another by an amount sufficient to produce an air dielectric between the windings that will resist high potential break-down stresses, and means for correcting the relationship between the primary and secondary current, said means comprising a condenser and a resistance connected in parallel relation to current in the primary winding.
  5. A transformer having a high tension, power current carrying, primary winding and a low tension secondary winding operatively related thereto, supporting means for

1. said windings arranged to support them out of contact with one another and separated from one another by an amount sufficient to produce an air dielectric between the windings that will resist high potential break-down stresses, and means for compensating for the difference in phase angle between the primary power current and the secondary current.
2. A transformer having a high tension, power current carrying, primary winding and a low tension secondary winding operatively related thereto and supporting means for said windings arranged to support them out of contact with one another and separated from one another by an amount sufficient to produce an air dielectric between the windings that will resist high potential break-down stresses and whereby the atmosphere is depended upon as the main insulation between said primary and secondary windings.
3. A transformer having a high tension, primary winding and a low tension secondary winding operatively related thereto, and supporting means for said windings arranged to support them out of contact with one another and separated from one another by an amount sufficient to produce an air dielectric between the windings that will resist high potential breakdown stresses.
4. A transformer having an iron core forming a substantially closed iron magnetic path, a primary coil having its windings encircling said core, a secondary coil having its windings also encircling said core, and supporting means for said windings arranged to support them out of contact with one another and separated from one another by an amount sufficient to produce an air dielectric between the windings that will resist high potential break-down stresses and whereby the atmosphere is depended upon as the main insulation between said primary and secondary windings.
5. A transformer having an iron core forming a substantially closed iron magnetic path, a primary coil having its windings encircling said core, a secondary coil having its windings also encircling said core, supporting means for said windings arranged to support them out of contact with one another and separated from one another by an amount sufficient to produce an air dielectric between the windings that will resist high potential break-down stresses and whereby the atmosphere is depended upon as the main insulation between said primary and secondary windings and means for correcting the relationship between the primary and secondary current.
6. A transformer having a high tension, power current carrying, primary winding and a low tension secondary winding, said windings being in the form of coils, each

passing substantially axially through the other substantially at right angles to one another and supporting means for said windings arranged to support them out of contact with one another and separated from one another by an amount sufficient to produce an air dielectric between the windings that will resist high potential break-down stresses and whereby the atmosphere is depended upon as the main insulation between said primary and secondary windings.

7. A transformer comprising a support, insulators secured to said support, a pair of retaining members spaced apart and secured to said insulators, a ring-shaped primary coil clamped between said retainers, and a ring-shaped secondary coil passing centrally through said primary coil, and supporting means for said windings arranged to support them out of contact with one another and separated from one another by an amount sufficient to cause the air space between the coils to serve as the main insulation therebetween.

8. A transformer having a substantially closed iron magnetic circuit, a high tension primary winding and a low tension secondary winding operatively related thereto, and supporting means for said windings arranged to support them out of contact with one another and separated from one another by an amount sufficient to cause the air space between the coils to serve as the main insulation therebetween.

9. A transformer having a substantially closed iron magnetic circuit, a high tension primary winding and a low tension secondary winding operatively related thereto and supporting means for said windings arranged to support them out of contact with one another and separated from one another by an amount sufficient to cause the air space between the coils to serve as the main insulation therebetween, and means for correcting the phase angle relationship between the primary current and secondary current.

10. A transformer comprising a base, spaced retainer members secured to said base between its ends, a ring-shaped secondary coil resting upon the base between said retainer members and arranged transversely with respect to said base, high tension insulators rising from the ends of said base, braces connected to said secondary coil at diametrically opposite points and extending inwardly for connection to said base, a pair of spaced retainer members secured to the upper end of each insulator, and a primary coil arranged at right angles to the secondary coil and secured between said last mentioned retainer members, said primary coil being ring-shaped and passing centrally through the secondary coil.

11. A transformer comprising a ring-

shaped primary coil, a ring-shaped iron core arranged at right angles to the primary coil and passing centrally therethrough, and a secondary coil wound transversely around said ring-shaped iron core and supporting means for said windings arranged to support them out of contact with one another and separated from one another by an amount sufficient to produce an air dielectric between the windings that will resist high potential break-down stresses.

In testimony whereof, we affix our signatures.

RICHARD C. DOWNING.
LLOYD C. NICHOLSON.
